CALCULATING MACHINE

Raymond A. Christian, Dayton, Ohio, assignor to
 The National Cash Register Company, Dayton,
 Ohio, a corporation of Maryland

Original application June 25, 1934, Serial No.
 732,252. Divided and this application July 24,
 1936, Serial No. 92,305

4 Claims. (Cl. 235—27)

This invention relates to improvements in accounting machines of the type illustrated and described in Letters Patent of the United States No. 1,203,863, issued November 7, 1916, to Halcolm Ellis, and United States Patent No. 1,819,084, issued August 18, 1931, to Emil John Ens. This case is a division of applicant's application Serial No. 732,252 filed June 25, 1934 which issued as Patent No. 2,082,098.

As disclosed in the present invention, the 10 Ellis type accounting machine is equipped with a traveling carriage and typewriter keyboard in addition to the regular adding machine keyboard. However, the typewriter attachment is a matter of choice and may be omitted where the business 15 system does not demand it.

In order to better adapt the Ellis machine for use by large department stores, banks, public utility companies and the like, who issue periodical statements to a plurality of customers, certain 20 novel improvements were provided, particularly in the traveling carriage and platen controlling mechanisms.

Therefore, it is broadly an object of this invention to incorporate in a machine of the type referred to various improvements to increase its 25 utility and flexibility so that it may be easily adapted for use in the majority of modern business concerns.

A further object is to supply adjustable stops for 30 use in connection with the selective controlling means and the skip-tabulating means.

Another object of this invention is to provide means to release the machine for operation by depressing certain control keys.

Still another object is to provide means whereby the traveling carriage in tabulated positions 35 controls depression of certain control keys.

A further object of this invention is to provide 40 novel control mechanism associated with a balance totalizer conditioning means.

With these and incidental objects in view, the invention includes certain novel features of construction and combinations of parts, the essential 45 elements of which are set forth in appended claims and a preferred form or embodiment of which is hereinafter described with reference to the drawings which accompany and form a part of this specification.

50 Of said drawings:

Fig. 1 is a cross sectional view of the machine proper taken just to the right of a row of amount keys.

Fig. 2 is a plan view of the machine control 55 keys.

Fig. 3 is a perspective view of the mechanism for releasing the machine for operation by means of the balance key and the mechanism for controlling depression of the balance key by means of the traveling carriage.

Fig. 4 is a detail view of the balance key and associated mechanism.

In the figure showing the framework in phantom by dot and dash lines, where the dot and dash lines do not show behind the parts it indicates that such parts are in front of the frames, but where the dot and dash lines are shown crossing the full line parts it indicates that such parts are behind the frames.

General description

An accounting machine, to be successfully used in present-day businesses, must not only be rugged and free from mechanical defects, but the success of such a machine depends largely upon such vital factors as accuracy, speed, and ease of operation. In accomplishing these results, various improvements have been made in the traveling carriage, platen roll, and machine controlling mechanisms, and it is to these improvements that the present invention is directed.

In its present embodiment, the machine of this invention is shown adapted for use by large department stores where charge accounts of a great number of individuals are carried from month to month. However, it is not desired to limit the machine of this invention to the particular use cited above, as the previously mentioned improvements widen the scope and increase the flexibility of the machine to the extent that it may easily be adapted for use in almost any business where it is necessary to frequently balance individual accounts and to make out statement slips or bills to be sent to a plurality of individual customers or patrons.

The balance key of the present machine, in addition to conditioning the balance totalizer for clearing operations, also, by means of mechanism shown in Fig. 3, releases the machine for operation by depressing the regular starting bar. A novel non-repeat mechanism prevents repetition of operation when the balance key is inadvertently retained depressed. In order to prevent the balance key from being depressed before the traveling carriage has had time to tabulate to the "Balance" column, mechanism has been provided to lock the balance key against depression until the "Balance" column is aligned with the printing mechanism. A stop on the traveling carriage,

cooperating with a hanging bar lever, then unlocks the balance key.

Detailed description

- 5 The mechanism of the machine of the present invention is supported between a left side frame 30 and a right side frame 31 (Fig. 3).
 10 The usual traveling carriage, a portion of which is shown in Fig. 3, carries a platen roll 40 (Fig. 1) which swings upwardly away from printing position so that record material may be inserted in the front thereof and pushed around the platen roll until the proper line thereof is in printing position. For a full disclosure of the front feed 15 platen mechanism, see the co-pending application of Raymond A. Christian, Serial No. 653,838, filed January 27, 1933.

Machine keyboard and operating mechanism

- 20 The machine of this invention has a plurality of denominational rows of amount keys 41, one of such denominational rows being illustrated in Fig. 1. The amount keys 41 are depressibly mounted by means of a top keyboard plate 42 having therein slots adapted to loosely support the upper end of said amount keys and by means of studs 43 secured in the lower ends of said amount keys cooperating with vertical slots in one of the keyboard side plates 44. The amount 25 keys 41 are flexible in that, after one key has been depressed in a particular row, depressing another key in that same row releases the first key depressed, and so on. Each amount key 41 has a spring 45 adapted to return and retain said 30 amount keys in their upward positions upon release thereof.

Depression of one of the amount keys 41 moves the stud 43 carried thereby into the path of one of a series of graduated steps 46 on an amount 40 rack 47 mounted for horizontal reciprocating movement by means of a rod 48 and a bar 49 supported by the main frames 30 and 31. The amount rack 47 has therein a vertical slot 50 which embraces a stud 51, secured in a segment 45 52 loose on a leading frame shaft 53, opposite ends of which are journaled in the frames 30 and 31. A spring 54 urges a projection 55 of the segment 52 into contact with the forward edge of a leading frame bail 56 extending between a pair of arms 57 (only one being shown) secured on the shaft 53.

Located on the right hand side of the keyboard is the usual starting bar 64 having stems 65 and 66, which are pivoted respectively to a plate 67 pivoted on a stud 68 secured in the frame 31, and an extension 69 of a lever 70 loose on a stud 71 also carried by the frame 31. The plate 67 carries a stud 72 which cooperates with the bifurcated end of an extension 73 of the lever 70. 55 Another extension 74 of the lever 70 carries a stud 75 which cooperates with the clutch release mechanism in the well known manner as shown and described in the patent of the United States No. 1,601,102 issued to F. W. Bernau on September 28, 1926.

Depressing the starting bar 64 rocks the plate 67 clockwise against the tension of a spring 76. The plate 67 in cooperation with the stem 66 of said starting bar, rocks the lever 70 in a counter-clockwise direction to move the stud 75 out of the path of the clutch releasing mechanism. This connects the clutch driven member to the driving member in the well known manner, thereby causing both members to be revolved in unison by the motor. Upon operation of the ma-

chine, the main drive shaft of the machine (disclosed in the parent application) is operated, and, through means also disclosed in the parent case, oscillates the shaft 53 first counter-clockwise and then clockwise to normal position.

By referring to Fig. 1, it is obvious that any movement of the shaft 53 is transmitted by means of the arms 57 to the bail 56 of the leading frame. Initial movement counter-clockwise of the bail 56, by means of the spring 54, causes the segment 52 to move in unison therewith, which, by means of the stud 51 and the slot 50, causes the amount rack 47 to move rearwardly until one of the graduated steps 46 engages the stud 43 of the depressed amount key 41. This 15 prevents further rearward movement of the amount rack 47 and the segment 52; consequently the bail 56 completes its rearward movement independently thereof, flexing the spring 54. In its return movement clockwise, the bail 56 20 picks up the segment 52 and returns said segment and the amount rack 47 to their normal, or zero, positions. In case no amount key is depressed, the zero stop lever retains the rack 47 in its zero position, as shown in Fig. 1, during machine operations.

The amount keys 41 position the rack 47 in the manner just described in adding and subtracting operations. In total taking operations, the proper denominational wheel of the selected 30 totalizer positions the rack 47 commensurate with the amount on said totalizer wheel in a manner presently to be described.

Totalizers

In its present embodiment the machine of this invention is equipped with two totalizers, an upper add-subtract or No. 1 totalizer and a lower adding or No. 2 totalizer (Fig. 1); however, it is merely a matter of assembly to equip the 40 present machine with additional totalizers. The No. 1 and No. 2 totalizers have respectively a plurality of wheels 80 and 81, only one of each here shown, adapted to be rocked into mesh with teeth 82 and 83 of the amount rack 47 in the 45 usual manner.

In adding operations, after the rack 47 has completed its initial movement rearwardly and has been properly positioned by one of the amount keys 41, as explained above, an alining 50 bar 84 connected by a pair of arms 85 to a shaft 86 is rocked into engagement with teeth 87 of the segment 52 to retain said segment and the amount rack 47 in their set position. Following this, the corresponding wheel to the selected 55 totalizer or totalizers is rocked into mesh with said rack, return movement forwardly of which rotates the wheel commensurate with the value of the depressed amount key.

In subtracting operations, the corresponding 60 wheel of the No. 1 or balance totalizer is rocked into engagement with the teeth 82 or the rack 47 before said rack starts its initial movement rearwardly. Initial movement rearwardly of the rack 47 revolves the wheel 80 of the No. 1 or 65 balance totalizer in a reverse or counter-clockwise direction until said rack 47 is stopped by the depressed amount key, as explained earlier herein. After the leading frame bail 56 and the rack 47 complete their initial movement rearwardly, the 70 wheel of the balance totalizer is disengaged from said rack 47. This results in the value of the depressed amount key being subtracted from the balance totalizer.

The wheels 80 (Fig. 1) of the No. 1 totalizer 75

each carries a tripping plate 88 with diametrically opposed tripping teeth which cooperate with add transfer pawls 89 and subtract transfer pawls 90 to transfer amounts from lower to higher denominations and to position the racks 47 in total taking operations in a manner presently to be described. In adding operations, the add transfer pawls 89 are rocked into the path of the teeth of the tripping plates 88, and the subtract pawls 90 are simultaneously rocked out of the path of the teeth of said tripping plates. In subtracting operations, the subtract transfer pawls 90 are moved into the path of the teeth of the tripping plate 88 and the add transfer pawls 89 are moved out of the path of said teeth.

Referring to Fig. 1, which, as previously stated, shows the mechanism for one denominational unit, in adding operations, when either of the teeth of the tripping plate 88 wipes past the tripping point of the adding transfer pawl 89, the transfer mechanism for the next higher denomination is tripped, thus causing one to be added in said next higher denomination. In subtract operations, when one of the teeth of the tripping plate 88 wipes past the subtract transfer pawl 90, the transfer mechanism for the next higher denomination is tripped, thus causing one to be subtracted from said higher denomination.

In total taking operations, the wheel 80 is engaged with the rack 47 prior to its initial movement rearwardly, which movement rotates said wheel 80 in a reverse or counter-clockwise direction until one of the teeth of the tripping plate 88 engages the inner surface of the tripping point of the add transfer pawl 89. This arrests the movement of the wheel 80 and positions the rack 47 and the segment 52 commensurate with the amount on said wheel 80. The wheel 80 is now in zero position and if the operation is a clearing or resetting operation, it is disengaged from the amount rack 47 before said rack starts its return movement forwardly. In reading or subtotal operations, the wheel 80 remains in engagement with the rack 47 during its return movement forwardly, consequently the amount is replaced thereon.

Each of the wheels 81 of the No. 2 totalizer carries a transfer tripping plate 91 similar to the plates 88 for the No. 1 totalizer wheels and having diametrically opposed teeth which cooperate with the tripping point of the No. 2 add transfer pawls 92 in adding and total taking operations in exactly the same manner as described for the No. 1 totalizer.

55 Printing mechanism

The printing mechanism will now be explained in connection with the mechanism shown in Fig. 1 for a particular denomination of the machine.

60 The segment 52 has an arm 93 pivotally connected by a link 94 to a type segment 95 pivoted on an arm 96 loose on a printer shaft 97 journaled in the right machine frame 31 and in the printer frames (not shown). The arm 96 carries a plate 98 with a projection 99 which cooperates with a printer release trigger 100, rotatably supported by the printer frame. The plate 98 has another projection 101 which cooperates with a zero elimination hook 102 loose on a shaft 103 supported by the printer frame. The hook 102 has a downward extension with an arcuate surface 104 which cooperates with a stud 105 carried by an extension 106 of the segment 52. Tensioned between a pawl 107 carried by the arm 96 and the bail 75 of a yoke 108 secured on the shaft 97 is a spring

109 which actuates the printing segment 95 and the arm 96 in a manner presently to be described.

In adding, subtracting, and total taking operations, initial movement rearwardly of the segment 52 (Fig. 1) and the amount rack 47 under influence of the leading frame bail 56, by means of the link 94, positions the printing segment 95 commensurate with the position of the amount rack 47. When the bail 56 reaches the terminus of its rearward movement, it dwells briefly in this position, and, during this dwell, clockwise movement of the shaft 97 and the yoke 108 rocks the release trigger 100 counter-clockwise to release the arm 96 and the printing segment 95 to the action of the spring 109, which has been given added tension by clockwise movement of the bail 108. The spring 109 urges the arm 96 and the segment 95 clockwise, causing said segment to make an impression upon material wound around the platen roll 40. Return movement counter-clockwise of the shaft 97 and the bail 108 restores the arm 96 and the printing segment 95 to the position shown in Fig. 1.

Whenever the segment 52 moves out of zero position, the stud 105, in cooperation with the arcuate surface 104 of the zero elimination hook 102, rocks said hook a slight distance counter-clockwise to disengage it from the projection 101 of the plate 98, thereby allowing the printing mechanism for that denomination to function. This counter-clockwise movement of the zero elimination hook 102 is imparted to the zero elimination hook of the next lower denomination when its segment 52 is retained in zero position. This allows the zeros of the lower order denominations to print and prevents the zeros of the higher order denominations from printing. When the segment 52 is returned to zero position, as shown in Fig. 1, a spring 117 restores the zero elimination hook 102 clockwise so that it engages the projection 101 of the plate 98.

Directing attention to Fig. 2, a row of control keys 118 and a No. 1 add key 119 located on the left hand side of the keyboard control the functions of the totalizers. The functions of the totalizers are also controlled by means of stops 120 in cooperation with the usual hanging bar levers. The stops 120 are adjustably supported in predetermined columnar positions by a stop bar 121 secured to the front of the traveling carriage which is not shown herein, but is shown in the parent case.

Traveling carriage mechanism

As previously brought out, the machine of this invention is provided with a traveling carriage of a type well known in the art and which is similar to that used on typewriters. The traveling carriage is adapted to be tabulated from column to column, and means are also provided to skip-tabulate the traveling carriage through one or more columnar positions at a time. Selectively controlled mechanism is provided to automatically return the traveling carriage from any tabulated position to an extreme right hand or starting position, or to other predetermined columnar positions. Mechanism is also provided to simultaneously effectuate the automatic platen feeding mechanism, the machine releasing mechanism, and the selective carriage returning mechanism simultaneously. Depression of the balance key is also controlled by columnar positions of the traveling carriage, and, in addition, means are provided whereby depression of 75

the balance key releases the machine for operation.

Balance key locking mechanism

5 In the machine of the present invention, mechanism has been devised to enforce the printing of the balance in a certain column of the record sheet. This mechanism is normally effective to lock the balance key against depression and is rendered ineffective only when the traveling carriage is tabulated to certain columnar positions.

10 Directing attention to Figs. 3 and 4, when the traveling carriage is tabulated to certain columnar positions, a downward projection 277 of the stop 120 engages an upturned extension 272 of a hanging bar lever 273 to rock said lever clockwise, as here observed, on its pivot 274 on the tabulating frame (not shown). Clockwise movement of the lever 273 lifts a hanging bar 275 which, by means of a stud 276 therein in operation with a slot in a plate 280, rocks said plate clockwise on its pivot stud 281 secured in the left frame 30. The rearward end of a pitman 282 is pivoted to the plate 280, while the forward end thereof is slotted to embrace a stud 283 in the frame 30. Consequently, clockwise movement of the plate 280 moves the pitman 282 rearwardly to disengage a right-angled projection 284 thereof from a notch 285 in the balance key 118. This unlocks the balance key 118 so that it may be depressed to print the balance in the proper column of the record material. When the traveling carriage is moved from this particular position and the stop 120 no longer engages the lever 273, a spring 286 returns the associated parts to normal position as here shown, so that the projection 284 of the pitman 282 will re-engage the notch 285 in the balance key 118.

40 *Machine release by balance key*

Referring to Figs. 3 and 4, depressing the balance key 118 moves the notch 285 therein opposite an extension 287 of a latch 288 loose on a stud 289 secured in the frame 30. This allows a spring 290 to rock said latch 288 clockwise, which, by means of a stud 291 in an extension 292 of said latch, in cooperation with an extension of an arm 293 secured on a shaft 294 journaled in the frames 30 and 31, rocks said shaft 294 counter-clockwise, as here observed. Secured on the right end of the shaft 294 is an arm 295 bifurcated to receive a stud 296 in the plate 67. It is therefore obvious that counter-clockwise movement of the shaft 294, by means of the arm 295, rocks the plate 67 clockwise, as observed in Fig. 3, to release the machine for operation in the usual manner. Near the end of a cycle of operation of the machine, lever 70 is rocked clockwise in the usual manner to restore the plate 67, and shaft 294, arm 295, and pin 291, and rocks the lever 288 counter-clockwise to move the extension 287 out of the notch.

It is generally the practice to allow the extension 287 of the latch 288 to bear directly upon the edge of the key stems, but in this instance the strength of the spring 290 is sufficient to overcome the action of the compression spring which returns the key 118 upwardly upon release thereof. If, under the above condition, the balance key 118 were partially depressed, it would be retained in that position, thereby causing an undesired effect and a possible jamming of mechanism upon operation of the machine. It was also found that accidentally or carelessly

retaining the balance key depressed at the end of machine operation prevented the proper functioning of the regular non-repeat mechanism and resulted in the jamming of the machine mechanism. Therefore, in order to overcome these undesirable conditions, means were provided to prevent the extension 287 of the latch 288 from bearing on the edge of the key stem and to make the restoring of the latch 288 at the end of machine operations independent of the release of the balance key 118. This latter is, in effect, an auxiliary non-repeat mechanism for the machine.

Describing in detail the mechanism outlined above, the spring 290 (Figs. 3 and 4) normally maintains the extension 287 of the latch 288 15 against a vertical surface 297 of a latch pawl 298 pivoted at 299 to the left frame 30 and urged clockwise by a spring 300 against a stop stud 301 secured in the frame 30. The pawl 298 has a notch 302 which cooperates with a bent-over ear 20 303 of a plate 304 urged clockwise by a spring 305 and rotatably supported by a bracket 306 secured on the stem of the balance key 118.

Depression of the balance key 118 causes the ear 303 of the plate 304 to engage the lower surface of the notch 302 to rock the latch pawl 298 counter-clockwise to disengage the surface 297 thereof from the extension 287 of the latch 288. This allows the extension 287 to enter the notch 285 in the stem of the key 118, and, in so doing, 30 said extension engages and rocks the plate 304 counter-clockwise to disengage the ear 303 from the latch 302 in the pawl 298. This frees the pawl 298 to the action of the spring 300 and when the latch 288 is restored counter-clockwise near the 35 end of machine operation, the pawl 298 snaps into position to hold the extension 287 out of contact with the stem of the key 118 and to prevent clockwise releasing movement of the latch 288 in case the balance key 118 is retained depressed 40 after operation is complete. It is therefore evident that the device just described prevents excessive drag on the stem of the balance key 118 and also serves as a non-repeat mechanism in case the balance key is inadvertently retained 45 depressed.

While the form of mechanism shown and described is admirably adapted to fulfill the objects primarily stated, it is to be understood that it is not intended to confine the invention to the 50 form or embodiment herein disclosed, for it is susceptible of embodiment in various forms all coming within the scope of the claims which follow.

What is claimed is:

1. In a machine of the class described, the 55 combination of a manipulative member with a recess; a latch resiliently urged towards the member and the recess; means to hold the latch away from the member when the same is in normal position; and means on the member effective upon manipulation thereof to disengage the holding means from the latch to allow said latch to enter the recess.

2. In a machine of the class described, the 60 combination of a manipulative member with a recess; a spring-urged element adapted to cooperate with the member and the recess; means normally holding the element away from the member to ease manipulation thereof; and means on the member effective upon manipulation 70 thereof to disengage the holding means from the element to allow the element to enter the notch, which movement of said element in turn disconnects the disengaging means from the holding means to allow the latter to engage the element 75

immediately upon restoration thereof to normal position.

3. In a machine of the class described, the combination of means to release the machine for operation; a latch cooperating with the releasing means; a manipulative member with a recess adapted to cooperate with the latch; yieldable means to move the latch into communication with the member and the recess; means to hold the latch away from the member to ease manipulation thereof; and an element on the member cooperating with the holding means to disengage the latter from the latch when the member is manipulated, thereby allowing the latch to enter the recess to operate the releasing means and to disengage the element from the holding means.
4. In a machine of the class described having a

totalizer and means to print balances standing on the totalizer, the combination of a manipulative device operable to condition the machine for a balance printing operation; a latch cooperating with the manipulative device, when said device is operated, and operable to retain the device in operated position during a balance printing operation; means normally retaining the latch out of cooperation with the manipulative device; means, operable when the device is operated, for removing the retaining means; a machine release means; and means, operable by the latch as it moves into cooperation with the device, to operate the release means to release the machine for a balance printing operation.
